(57) **CLAIM**

The ornamental design for an exercise device having caster-supported platform with resistance band catch, as shown and described.

DESCRIPTION

FIG. 1 is a perspective view of an exercise device having caster-supported platform with resistance band catch according to my new design;

FIG. 2 is a perspective view of an underside of the exercise device having caster-supported platform with resistance band catch of FIG. 1;

FIG. 3 is a front elevational view of the exercise device having caster-supported platform with resistance band catch of FIG. 1, the elevational views of the exercise device having caster-supported platform with resistance band catch rotated 120° and 240° from the front elevational view being an identical image thereof;

FIG. 4 is a rear elevational view of the exercise device having caster-supported platform with resistance band catch of FIG. 1, the elevational views of the exercise device having caster-supported platform with resistance band catch rotated 120° and 240° from the rear elevational view being an identical image thereof;

FIG. 5 is a left side elevational view of the exercise device having caster-supported platform with resistance band catch of FIG. 1, the right side elevational view being a mirror image thereof;

FIG. 6 is a perspective view of the exercise device having caster-supported platform with resistance band catch of FIG. 1 to which a resistance band is connected, the phantom showing of the resistance band forming no part of the claimed design; and,

FIG. 7 is a partial perspective view of the exercise device having caster-supported platform with resistance band catch of FIG. 2 showing a resistance band hooked on the resistance band catch, the phantom showing of the resistance band forming no part of the claimed design.

The broken lines in the drawings illustrate portions of the article that form no part of the claimed design.

1 Claim, 5 Drawing Sheets
